Patented Apr. 18, 1922.

UNITED STATES PATENT OFFICE.

SAMUEL BERGER, OF NEWARK, NEW JERSEY, ASSIGNOR, BY MESNE ASSIGNMENTS,
TO ILLINOIS WATCH CASE COMPANY, OF ELGIN, ILLINOIS, A CORPORATION OF
ILLINOIS.

CIGARETTE CASE.

1,413,381.

Specification of Letters Patent. Patented Apr. 18, 1922.

Application filed October 10, 1917. Serial No. 195,752.

To all whom it may concern:

Be it known that I, SAMUEL BERGER, a citizen of the United States, and a resident of Newark, in the county of Essex and State 5 of New Jersey, have invented certain new and useful Improvements in Cigarette Cases, of which the following is a specification.

This invention has for its object to provide a simple, inexpensive, neat and efficient 10 case for cigarettes and other articles, and particularly a case of the type comprising two hinged lids and a holder arranged to take automatically a position equidistant from the lids, when the case is opened.

15 An example of a cigarette case embodying my invention is shown in the accompanying drawings in which Fig. 1 is a section taken substantially on the plane indicated by the line 1—1 of Fig. 2, the latter being an inside 20 view of the case, with one of the lids removed and parts of the hinge in section; Fig. 2 shows the case closed, while Fig. 1 represents it open; Figs. 3 and 4 are detail sections, on an enlarged scale, taken on lines 3—3 and 25 4—4 respectively of Fig. 2; Fig. 5 is a detail perspective view showing one of the hinge connections of the holder; Figs. 6 and 7 are 30 sectional views similar to Figs. 3 and 4, but showing the position assumed when the case 35 is open; Fig. 8 is a partial section on line 8—8 of Fig. 1; and Fig. 9 is a section on line 9—9 of Fig. 2.

In the particular embodiment illustrated, 40 the case comprises two lids A, B, provided with flanges or bezels A', B' respectively and with hinge eyes A'', B'' respectively, the hinge eyes B'' appearing in section in Fig. 2. One of these hinge eyes A'' and one of the hinge eyes B'', are of a special novel construction, to co-operate with certain parts 45 of the holder for the purpose of giving it a central position when the case is opened, as fully explained below. A suitable pintle C completes the hinge connection of the lids A, B.

Connected with the hinge of the lids, and located between them, is the cigarette holder proper, which, as shown, may consist of two members D, E fastened together by soldering 50 or in any other suitable manner, and provided with sockets D', E' to seat the cigarettes F, two rows of five each being accommodated in the particular case shown. At their ends the holder members may have 55 bent lugs D'', E'' to assist in keeping the

cigarettes in place. At their edges, the members D, E have hinges G', H' for flaps G, H pressed inwardly by springs G'', H'', the hinges G', H' being parallel to the hinge of the lids. For the sake of clearness, these 60 flaps and their hinges have been omitted from Figs. 3, 4, 6, and 7.

To connect the holder with the hinge of the lids, I provide two brackets J, K having hinge eyes J', K' respectively, fitted between 65 hinge eyes of the lids. According to my invention, each of the hinge eyes J', K' is provided at one side with a segmental extension J'', K'' respectively, and the adjacent hinge eye B'', A'' respectively has a 70 corresponding lateral segmental projection b, a respectively, that is to say, the mating extensions J'', a and K'', b respectively lie in the same transverse plane and are thus adapted for co-operation with each other. 75 The two pairs of mating projections are arranged reversely, that is to say, if the projection J'' extends on the right-hand side of the hinge (Figs. 3 and 6), then the projection K'' will be on the left-hand side 80 (Figs. 4 and 7), and the projections a and b will be to the left and right respectively. The two segmental projections of the same 85 pair are preferably of different angular extent, and their aggregate extent is less than 360°, so that a space for relative movement is left as shown clearly in Figs. 3, 4, 6 and 7. The angular extent of this space is one-half of the angular extent of the lid movement; that is to say, if the lids are intended to 90 open to about 90°, as shown, then the angular extent of the space between the projections J'', a and K'', b respectively, will be about 45°.

The operation of this feature will be 95 understood readily, particularly with reference to Figs. 3, 4, 6 and 7. The gaps or free spaces between the hinge projections J'', a and K'', b allow the holder to move relatively to the lids as the latter open. When the 100 fully-open position is reached (Figs. 1, 6 and 7), the segmental extension a of the one hinge eye A'' engages the right-hand edge of the mating extension J'' on the hinge eye J' of the bracket J. At the same time, the 105 extension b of the one hinge eye B'' engages the left-hand longitudinal edge of the mating extension K'' on the hinge eye K' of the bracket K. Since the brackets J, K are rigid with the holder, the 110

latter is virtually engaged on opposite sides by the projections b , a of the lid hinges, and a two-fold result is obtained: First, the opening movement of the lids is arrested or limited; second, when the lids are in this fully open position, the holder is maintained steady and practically rigid in a position midway between the lids. The two brackets J , K , being rigid with the holder, as stated above, and the hinge eyes J' , K' with their projections J'' , K'' therefore being likewise rigid with each other, it follows that the two parts or surfaces of the holder which, in the open position of the case are engaged by the two lids, or by their hinge eye projections a , b , are rigid with each other. It will be noted that these desirable results are obtained by the use of a very simple and inconspicuous construction. In the closed position of the case (Figs. 3 and 4) the brackets J , K may be engaged by the bezels A' , B' and held firmly between them, but this is not essential.

Any suitable means may be employed for normally keeping the case closed and causing it to open when desired. I have shown a spring catch L on the lid A , to co-operate with a suitable keeper on the lid B . A spring M having its ends fitted to the bezels A' , B' respectively and bent around one end of the brackets J serves to open the lids A , B when the catch L is released. This spring has been omitted from Figs. 3 and 6. As this spring embraces the said brackets J , it has a tendency to keep the holder equidistant from the lids, whether the case is open or closed, or in any intermediate position. However,

the holding action of the yielding spring M is not positive, as is that of the projections J'' , a , K'' , b in the open position of the case. I therefore consider the holding action of the spring (to keep the holder midway between the lids) as incidental, the main function of this spring being to secure the opening of the lids, and the mating projections J'' , a , K'' , b will suffice to keep the holder equidistant from the lids when the case is open. The spring M might be arranged in other ways, and not necessarily in the relation illustrated to one of the holder brackets.

Various modifications may be made without departing from the nature of my invention as set forth in the appended claims.

I claim:

1. A case for cigarettes or other articles, comprising a pair of lids and a holder located between them, all three provided with aligning hinge eyes, means for connecting said eyes, the holder being provided with a bracket extending to the hinge, and a spring whose ends bear on the respective lids to open the case, while the central portion of the spring is bent to embrace said bracket.

2. A case for cigarettes and other articles, comprising a pair of hinged lids provided with bezels adjacent to the hinge, a holder located between the lids and having a bracket pivoted to the lid hinge, and a spring straddling the holder bracket and having its ends connected with the bezels of the respective lids.

In testimony whereof I have signed this specification.

SAMUEL BERGER.
